UNITED STATES PATENT OFFICE.

CLYDE W. KELLER, OF KANSAS CITY, MISSOURI.

MIXING DEVICE.

Application filed July 19, 1926. Serial No. 123,299.

My invention relates to improvements in mixing devices.

One of the objects of my invention is to provide a novel mixing device adapted for insertion between a carburetor and a manifold, whereby water, preferably in vapor form, and air may be intimately mixed with the fuel mixture drawn from the carburetor into the manifold.

10 A further object of my invention is to provide a mixing device of the kind described, which is simple, cheap, durable, which is not liable to be clogged, which will effect a thorough intermingling of the fuel mixture with 15 water vapor or water vapor and air, or of air alone, which is durable and not liable to get out of order, and which can be easily and readily applied by an unskilled person to explosive engines now in use.

20 The novel features of my invention are hereinafter fully described and claimed.

In the accompanying drawing, which illustrates the preferred embodiment of my invention,

25 Fig. 1 is a side elevation of my improved mixing device shown mounted in operative position between a carburetor and manifold of usual type.

Fig. 2 is an enlarged central vertical sectional view of the same.

Fig. 3 is an enlarged perspective view of the mixing device with the fans, washers, and pins removed.

30 Fig. 4 is an enlarged view partly in longitudinal section and partly in elevation of my improved mixing device.

Similar characters of reference designate similar parts in the different views.

My improved mixing device is provided 40 with a plate 1, which is adapted to be inserted, as shown in Figs. 1 and 2 between a carburetor C and a manifold M, the ends of the plate having respectively two notches 2 adapted to receive the securing bolts, one of which, designated by B, is shown in Fig. 1, which fasten the carburetor to the manifold. Gaskets 3 may be inserted between the plate 1 and the manifold and carburetor.

45 The plate 1 is provided with a bridge portion 4, which extends transversely across a passage 5 through the plate 1, said passage serving to connect the passages of the carburetor and the manifold.

50 The bridge portion 4 is centrally disposed and at opposite edges is respectively provided

with two horizontal bearings, which may be oppositely extending central trunnions 6, which may be integral with the bridge portion 4, and upon which are respectively rotatably mounted two fans 7 and 8, which are, 60 preferably, provided with oppositely disposed blades 9 and 10, by means of which a current of fluid passing through the passage 5 will rotate the fans in opposite directions.

For holding the fans on the trunnions, the 65 latter are respectively provided with transverse holes in which are fitted cotter pins 11. Intermediate of the pins 11 and the fans on the trunnions 6 respectively are mounted washers 12.

70 The plate 1 is provided with a lateral threaded hole 13 communicating with the passage 5 at one side of and adapted to discharge water vapor or air or both simultaneously against one side of the bridge portion 4, 75 which is disposed transversely to said hole. The hole 13 provides an inlet for the water vapor so arranged that the bridge portion 4 will serve to deflect and diffuse the fluid discharged from the inlet into the passage 5.

80 As the water vapor and air is diffused by striking the bridge portion 4 it will be thoroughly intermingled with the current of fuel mixture which is passing through the passage 5. The fan 7 revolving in one direction will 85 tend to intermingle and revolve the fuel mixture and the water vapor and air in one direction, and the fan 8 will, by revolving in the opposite direction, effect a still better admixture of the vapor air and fuel mixture. 90

As shown, the blades 9 and 10 of the fans may each have perforations, 14, to reduce the resistance offered by the blades to the suction effect of the engine, and to assist in the intermingling of the vapor, air and fuel mixture. 95

100 In the operation of the mixer, when the engine effects a suction through the passage 5 from the carburetor C, the fans 7 and 8 will be revolved in opposite directions, thus intermingling the water vapor and air entering the passage 5 through the inlet hole 13, the vapor and air on striking the bridge portion will be deflected and diffused between the fans, thereby making more perfect the 105 thorough intermingling of the vapor and air with the fuel mixture. The bridge portion 4, thus located, effects the double function of a deflector and mixer and of a support for the fans.

In the threaded hole 13 may be fitted a suitable connector, such as the nipple 15, shown, which may be connected with any suitable conductor for water and air deriving its supply of water from any suitable source, not shown.

As the bridge portion 4 is provided with integral trunnions, and the fans are retained thereon by washers held in place by cotter pins, there are no parts which are liable to become loose, and a simple cheap structure is afforded.

I do not limit my invention to the structure shown and described, as modifications, within the scope of the appended claim, may be made without departing from the spirit of my invention.

What I claim is:—

In a mixing device, a plate adapted to be disposed between a carburetor and an intake manifold, and having a passage therethrough adapted to align with the intake passages of the carburetor and the manifold, and having a bridge portion extending diametrically across said passage and having at opposite edges two central longitudinal trunnions, said plate having a vapor inlet intermediate of said edges and discharging against the adjacent side of said bridge portion, and two fans respectively freely rotatable on said trunnions.

In testimony whereof I have signed my name to this specification.

CLYDE W. KELLER.
